UNITED STATES PATENT OFFICE.

GEORGE R. WAALER, OF CHICAGO, ILLINOIS, ASSIGNOR TO CRYSTAL FIXTURE CO., OF CHICAGO, ILLINOIS, A CORPORATION OF ILLINOIS.

DESIGN FOR A LEG FOR DISPLAY STANDS OR SIMILAR ARTICLES.

Application filed September 5, 1925. Serial No. 14,715. Term of patent 3½ years.

To all whom it may concern:

Be it known that I, GEORGE R. WAALER, a citizen of the United States, residing at Chicago, in the county of Cook and State of Illinois, have invented a new, original, and ornamental Design for a Leg for Display Stands or Similar Articles, of which the following is a specification, reference being had to the accompanying drawing, forming a part thereof.

Fig. 1 is a side elevation of my ornamental leg for display stands or similar articles; and

Fig. 2 is a front elevation of the same.
I claim:

The ornamental design for a leg for display stands or similar articles, as shown.

GEORGE R. WAALER.
